UNITED STATES PATENT OFFICE

CLAUDE L. HARRINGTON, OF DETROIT, MICHIGAN, ASSIGNOR TO WHITE STAR REFINING COMPANY, OF DETROIT, MICHIGAN, A CORPORATION OF DELAWARE

VALVE DEVICE

Application filed May 11, 1928. Serial No. 276,874.

This invention relates to a valve device and more particularly to a construction thereof tending to simplify, render more efficient and improve the same generally.

5 The device relates particularly to a back-flow check valve finding particular utility in connection with measuring pumps, such as now generally employed for dispensing gasoline and the like.

10 The device has as one of its primary objects to provide a simple and efficient construction which may be quickly and economically manufactured, assembled and repaired with facility and which will efficiently 66

15 perform its intended functions.

The several objects, advantages and novel details of this invention will be made more apparent as this description proceeds, especially when considered in connection with 65

20 the accompanying drawing, wherein;

Figure 1 is a semi-diagrammatic view illustrating the application of my improved device;

25 Figure 2 is an enlarged vertical sectional elevational view of my improved valve device, showing the parts thereof in one position; and

Figure 3 is a similar view showing the parts in another position.

30 Referring now to the drawing and more especially to Figure 1, it will be noted that there is illustrated generally a gasoline dispensing pump 10 having a suction or supply line 11 extending to and within a gasoline 80

35 tank 12. The end of the supply or suction line 11 is adapted to be connected to my improved valve device indicated generally by 85

the reference character 13.

By reference to Figures 2 and 3 it will be 40 noted that the valve device consists essentially of a sleeve-like housing 14 having an upper interiorly threaded portion adapted for threaded engagement with the lower end of the suction line 11. The lower end of the 90

45 housing 14 is internally threaded for engagement with the externally threaded portion of a nipple 15. The other or lower end of the 95

50 16 of a strainer 17. The upper end of the

nipple 15 is also internally threaded for engagement with the externally threaded portion of a sleeve-like member 18 provided with one or more outlet ports 19. The outer surface 20 of the member 18 is preferably accurately machined or finished so as to provide for a close engagement or sliding fit between this surface and the inner surface 21 of a cap-like valve member 22 adapted for sliding telescopic engagement with the member 18. The lower edge of the valve member 22 is bevelled or inclined as indicated at 23 for engagement with a similarly shaped shoulder 24 formed on the member 18. When the surface 23 of the valve member 22 engages shoulder 24 further downward movement of valve member 22 is prevented and the engagement of these surfaces 23-24 is such as to prevent the escape of liquid therebetween. The upper end of member 18 is 70

closed with the exception of an aperture 25 which prevents the formation of a vacuum between the upper end of member 18 and valve member 22 as the latter is raised to uncover outlet ports 19.

Arranged in the upper end of housing 14 75

is a yoke or other supporting means 26 provided with a threaded aperture for engagement by a set screw 27. This set screw acts as an adjustable abutment for limiting the upward movement of valve member 22 as will be obvious. The upward movement of valve member 22 is caused by the suction in suction line 11 whereas when this suction is interrupted valve member 22 will seat by 80

gravity and thus cover ports 19.

A device of this character finds particular utility in connection with measuring pumps used for instance in dispensing gasoline, because with such a construction the suction 90

line 11 may be maintained full of liquid as the valve 22 prevents this liquid from draining back into the tank 12 when suction on the suction line 11 is interrupted. This insures rapid and accurate measurement of the liquid being dispensed.

Obviously the herein described construction lends itself to rapid and economical production and easy assembly. Should any of the parts become broken or worn the device 100

may be readily disassembled and new parts substituted for the broken or worn ones. The construction of the valve is such that a double check is provided in that the flow of the liquid through the outlet ports 19 is first interrupted when cap-like valve member 22 covers ports 19 and is further checked when valve surface 23 engages valve surface 24.

5 Obvious changes will suggest themselves to those skilled in this art and to this end 10 reservation is made to make such changes as may come within the purview of the accompanying claim.

What I claim as my invention is:

15 In a device of the class described, a casing provided with an open end, a member arranged within said casing and provided with a port, a second member telescopically engaging said first-mentioned member and operable to control the flow of fluid through 20 said port, and means arranged entirely within said casing for limiting the opening of the valve including a member threadedly engaging the inner wall of said casing and an adjustable stop carried by said member and engageable with said second member.

25 In testimony whereof I affix my signature
CLAUDE L. HARRINGTON.
